FIG. 3

UNITED STATES PATENT OFFICE

2,376,269

GARMENT HANGER

Theodore C. Pauli, Kirkwood, Mo., assignor to
 Orchard Paper Company, St. Louis, Mo., a corporation of Missouri

Application May 15, 1943, Serial No. 487,091

3 Claims. (Cl. 223—88)

This invention relates to improvements in hangers generally employed for supporting articles of clothing in the well-known manner, and more particularly to such devices that may be constructed from materials which are nearly always available in sufficient quantity, even when metals and similar materials are restricted as to such use or are unobtainable or undesirable for any reason.

The invention has among its principal objects the production of a garment hanger made principally or entirely of paper or similar material, that will be simple and inexpensive, of few parts, durable and sturdy for its intended functions, neat in appearance, and which will be otherwise satisfactory and efficient for use wherever deemed applicable.

One of the main objects of this invention is to form such a garment hanger from a length of hollow spirally-wound tubing of paper material, and while the adhesive used in the making of such tubing is still moist, shaping and forming the various points or portions of said length of tubing to the desired configuration and interlocking with the supporting hook, and maintaining the tubing in such shape until the adhesive has dried, whereupon the parts so formed will be sufficiently rigid to continue to hold their shape in service.

Another object of my invention is the process of so forming and shaping and assembling the parts of the garment hanger while the tubing is moist and before the adhesive has set and dried.

An added object of my invention is to construct a hanger of the kind described, having a cross member and a pair of side members connected to the ends thereof and converging therefrom to securement with the supporting hook, wherein the side members will be of hollow tubular paper material having their lower portions compressed to substantially fully flattened shape thereat and curved downwardly and outwardly toward the connections to said cross member.

A further object of this invention is to construct a garment hanger of paper tubing, and to have the same interlock with a supporting hook flattened adjacent its base, said base constructed with feet divergent therefrom, not only wider than the diameter of the hanger tubing, but additionally provided with lugs, the respective ends of the tubing provided with slots and notches, so that the tubing may be compressed upon insertion of the divergent feet of the hook thereinto, whereupon the lugs will snap into said slots to limit longitudinal movement therebetween and

the notches will straddle the sides of said hook.

Many other objects and advantages of the construction herein shown and described, and the uses mentioned, will be obvious to those skilled in the art to which this invention appertains, as will be apparent from the disclosures herein given.

To this end, my invention consists in the novel construction, arrangement and combination of parts herein shown and described, and the method of making the same, as will be more clearly pointed out in the claims hereunto appended.

In the drawing, wherein like reference characters indicate like or corresponding parts throughout the views,

Figure 1 is a perspective view of the hanger; Figure 2 is an enlarged fragmentary detail of the upper part of the same, with a part of one of the side members of the hanger frame in section; and

Figure 3 is an enlarged fragmentary detail, partly in section, of the adjoined cross member and one of the pair of side members.

Referring more particularly to the drawing, wherein I have illustrated a preferred embodiment of my invention, there is shown a length of hollow tubing, preferably of a strip of paper material or the like and spirally or convolutedly wound or otherwise suitably formed to the desired wall thickness, using any desired adhesive during the manufacture of the same, this length of tubing bent to form a lower or cross member 1 and a pair of side members 2—2 adjoined to its ends and converging upwardly therefrom to form a substantially triangular frame. If desired, the tubing may have an outermost ply or layer 3, plain or ornamented, and also preferably of paper, and generally applied before the adhesive of the tubing has set.

In order to have the garment-shoulder engaging portions of the hanger as broad as possible, and rounded thereat, the lowermost portions of the side members 2—2 are preferably compressed until they are substantially flattened, somewhat

as indicated at 4, and curved outwardly and downwardly toward the juncture with the cross member 1, and are held in this curved and compressed shape until the hanger is dried thereat. When thus shaped and dried, the hanger will hold its shape, aided by the setting and drying of the adhesive thereat, as well as the paper itself, and there will be a desired flexibility of the hanger thereat, too, all without any fracturing or rupturing of the fibers of the paper at said regions.

Each of the uppermost or open ends of the side

members 2—2 is provided with a notch 5 extending inwardly of the open end, and in addition a slot or opening 6 is provided through the side wall of the tubing and rearwardly or inwardly of said notch, all of said notches and slots preferably being in a common plane, for a purpose to be immediately described.

A supporting or suspension hook 7, preferably of paper cardboard, or the like, or in fact, of any desired material, is provided for completing the assembly of the hanger, and whereby the same may be suspended from a rod or the like in actual service, said hook having a lower portion preferably flattened so as to lie in a plane, and with a pair of oppositely directed or divergent feet 8—8 at its base. It is to be particularly noted at this point, that the width of said feet is greater than the normal diameter of the paper tubing of the side members 2—2, so that the latter members must be compressed to increase the width of opening and permit insertion of the divergent feet thereto, in assembly.

In addition, lugs 9 are formed on each of said feet, projecting laterally from the width of said feet, the lugs preferably having their forward or leading edges of less width than their rearward or trailing edges, and sloping rearwardly (of the direction of insertion), so as to permit easier insertion of the divergent feet into the respective ends of the side members 2—2, the lugs snapping into place to extend through the slots or openings 6—6, and the notches 5—5 straddling the flattened lower portion of the hook element, as shown.

The lower portion of the hook may be coated with adhesive or not, as desired, before assembly with the side members of the hanger frame, and this insetting is preferably done while the side members are still moist and pliant, so that the step is simplified and there is little or no danger of rupture of the tubing while expanding or flattening it thereat, and there is a very good interlocked connection as soon as the drying is completed.

Having thus described my invention, it is obvious that various immaterial modifications may be made in the same without departing from the spirit of my invention; hence I do not wish to be understood as limiting myself to the exact form, arrangement, construction and combination of parts herein shown and described, or the exact method of making the same, except as limited by the state of the art to which this invention appertains, and the claims hereunto appended.

What I claim as new and desire to secure by Letters Patent is:

1. In a garment hanger, a cross member and a pair of tubular side members connected thereto and converging therefrom, the open ends of said side members having notches through the walls, and each end provided with a slot through said tubular wall and spaced inwardly from said notch, said slots and notches being substantially in alignment, and a hook with a flattened base for securing to said side members and whose base is of substantially the same thickness as the width of said notches and has a pair of divergent feet with projecting lugs for insertion into the opposed ends of said side members of the hanger, whereby when the feet are inserted into the open ends of said side members, said lugs will project through the respective slots and the notches will straddle and engage the flattened sides of the base of said hook.

2. In a garment hanger made of a length of paper tubing bent to form a cross member and a pair of convergent side members, each of the free ends of said side members provided with a notch extending thereto and with a slot through the tubular wall and spaced inwardly of the tube end, all of said slots and notches being substantially in a plane, and a supporting hook with a flattened base for securing to said free ends of the said side members, said base formed into a pair of divergent feet with lugs projecting therefrom, each lug being wider at its trailing edge than at its forward edge and whereby said divergent feet may be inserted into the open ends of said side members until said lugs snap through said slots and interlock against longitudinal movement in either direction and the notches will straddle said hook base.

3. In a garment hanger made of a length of paper tubing bent to form a cross member and a pair of convergent side members, each of the free ends of said side members provided with a radial slot through said tubing and spaced inwardly of the tube ends, a supporting hook with a flattened base for insertion into the tube ends for securing, said base formed into a pair of divergent feet with lugs projecting therefrom and each lug being wider at its trailing edge than at its forward edge, whereby said divergent feet may be inserted into the open ends of said side members until said lugs snap through said slots and interlock with said side members against longitudinal movement in either direction.

THEODORE C. PAULI.
